CLAIM

The ornamental design for an electronic device, as shown and described.

DESCRIPTION

FIG. 1 is a first front perspective view of the electronic device;

FIG. 2 is a front view thereof;

FIG. 3 is a back view thereof;

FIG. 4 is a top view thereof;

FIG. 5 is a bottom view thereof;

FIG. 6 is a right-side view thereof;

FIG. 7 is a left-side view thereof; and,

FIG. 8 is a second front perspective view thereof.

The additional broken lines in FIG. 8 showing the cord and the upright transaction terminal depict environmental structure only and form no part of the claim, while all other broken lines in the drawings depict portions of the electronic device that form no part of the claimed design.

The unshaded surfaces seen inside the card slot are not claimed.
